UNITED STATES PATENT OFFICE

2,603,981

STEERING LEVER CONSTRUCTION

Merton F. Snyder, Minneapolis, Minn., assignor
to Scott-Atwater Manufacturing Company,
Minneapolis, Minn., a corporation of Minnesota

Application April 22, 1946, Serial No. 664,143

9 Claims. (Cl. 74—551.3)

1

This invention relates to an outboard motor and particularly to a structure of steering arm and handle of such a motor.

It is an object of this invention to provide a structure of outboard motor having a steering arm, a handle connected at one end to said arm and movable to steering position in substantial longitudinal alignment with said arm and movable to carrying position substantially at right angles to said arm.

It is a further object of the invention to provide such a structure as set forth in the preceding paragraph, together with simple and efficient means for locking said handle in said carrying position.

It is another object of the invention to provide an outboard motor structure comprising a substantially vertically extending drive-shaft, a steering arm extending substantially perpendicular to said shaft, a handle connected at one end to said arm by a pivot extending transversely thereof so that said handle can be moved to steering position in substantial longitudinal alignment with said arm and to position substantially at right angles to said arm, one of said members having an opening extending longitudinally thereof and the other of said members having a portion receivable in said opening, and means carried by one of said members and movable to position to lock said handle in said last mentioned position.

It is more specifically an object of the invention to provide an outboard motor structure comprising a steering arm, a handle pivoted at one end to said arm by a transverse pivot so that said arm is swingable to a position in substantial longitudinal alignment with said arm and to a position substantially at right angles to said arm, said handle having a slot extending longitudinally thereof at said end, said arm having a portion receivable in said slot when said arm is in said first mentioned position, a sleeve rotatably carried on said handle having a slot therein through which said portion passes, said sleeve being movable to position to bring the said slot therein out of alignment with said portion when said handle moves to said last mentioned position to lock said handle in said last mentioned position, stops preferably being provided for said sleeve.

These and other objects and advantages of the invention will be fully set forth in the following description made in connection with the accompanying drawings in which like reference characters refer to similar parts throughout the several views and in which:

2

Fig. 1 is a perspective view of an outboard motor having the invention applied thereto;

Fig. 2 is a view in side elevation of a portion of the steering arm and handle of said motor;

Fig. 3 is a partial view similar to Fig. 2, some parts being broken away and others shown in vertical section;

Fig. 4 is a central vertical section of said arm and handle;

10 Fig. 5 is a partial bottom plan view of said arm and handle, some parts being broken away and others shown in horizontal section;

Fig. 6 is a vertical section taken on line 6—6 of Fig. 8 showing the handle in a different position,

15 Fig. 7 is a horizontal section taken on line 8—8 of Fig. 6, as indicated by the arrows; and

Fig. 8 is a view similar to Fig. 7, with parts shown in different positions.

20 Referring to the drawings, in Fig. 1, an outboard motor 10 is shown comprising the driving shaft and exhaust housing 10a, the cylinder block 10b, the gas tank 10c and propeller 10d. The clamp 10e for clamping the motor to a boat

25 is also shown. Said motor 10 comprises a driving shaft 10f, which, when the motor is in operating position on a boat, extends substantially vertically. A steering arm 11 is shown which will be constructed and arranged to turn a tube 10j secured in a sleeve 10h forming a portion of housing 10a. Steering arm 11 is secured to sleeve

30 10h by screws or bolts 10g. While steering arm 11 could be variously formed, in the embodiment of the invention it is illustrated as a flat bar. A handle 12 is provided, the same having a stem or core 12a which is bifurcated at one end and thus provided with spaced ears or lugs 12b. Handle

35 12 is pivotally connected to arm 11 by a pivot comprising a headed and nutted bolt 13 extending transversely through lugs 12b and arm 11. The head of bolt 13 and the nut thereon are respectively received in recesses in lugs 12b.

Handle 12 can thus be swung to steering position, as shown in dotted lines in Fig. 1, in which 40 it is in substantial longitudinal alignment with arm 11, and it can be swung to carrying position, as shown in full lines in Fig. 1 and also in Fig. 6 in which it is substantially at right angles to arm 11. Member 12a is provided with a central longitudinal slot 12c adjacent the lugs 12b,

45 and arm 11 has a terminal portion or projection 11a which is receivable in slot 12c. When handle 12 is in steering position, portion 11a is disposed in slot 12c, as shown in Fig. 4, and the inclined end surface of portion 11a engages the inclined surface 12d at the bottom of slot 12c, as

shown in Fig. 4. A sleeve 14 is rotatably mounted on a cylindrical portion 12e of member 12a adjacent the lugs 12b and said sleeve is provided at one side with a slot 14a extending from its outer end, which slot is somewhat wider than the thickness of arm 11, as shown in Fig. 5. When handle 12 is in the position shown in Fig. 4, portion 11a of arm 11 is received in slot 14a. A collar 15 is secured to portion 12e, which collar is secured by spaced screws 16. Collar 15 has a lug 15a projecting at the side thereof adjacent sleeve 14 and sleeve 14 is provided with a peripheral groove 14b in which lug 15a is disposed. Lug 15a forms a stop for limiting the positions of sleeve 14 when it is rotated on portion 12e. Portion 12e is provided with a shallow peripheral slot 12f in which is disposed a semi-cylindrical or bow spring 17 which is engaged by sleeve 14. Spring 17 provides friction for sleeve 14 so that it is not too easily moved. Handle 12 also comprises a grip portion 12g surrounding the outer portion of stem 12a, which portion 12g will be made of wood, rubber composition or plastic.

In operation when handle 12 is in steering position it will occupy the position shown in Figs. 3 and 4. As stated, at this time portion 11a of arm 11 extends through slots 12c and 14a and the surface 12d of handle 12 engages the end of arm 11. The handle 12 will remain in said position and the boat can now be steered by moving handle 12 and arm 11 about the axis of shaft 10f. Handle 12 can be swung to the position shown in full lines in Fig. 1 and also shown in Fig. 6. At this time portion 11a is not disposed in the slot 12c and sleeve 14 can now be rotated to bring slot 14a out of alignment with portion 11a so that handle 12 cannot be swung to or toward the position shown in Fig. 4. The end of sleeve 14 now engages the side of arm 11, as shown in Fig. 6, so that handle 12 is locked in the position shown in Fig. 6. When handle 12 is in the position shown in Fig. 6 and in full lines in Fig. 1, it forms a very convenient carrying handle for the motor. The motor is nicely balanced about the end of arm 11 and the motor can now be carried with shaft 10f extending substantially horizontally. It is thus unnecessary to provide any other carrying handle for the motor. Handle 12 functions both as a steering handle and as a carrying handle. Sleeve 14 is stopped in one position by lug 15a engaging one end of groove 14b with slot 14a aligned with arm 11. Said sleeve 14 is stopped in another position by lug 15a engaging the other end of groove 14b with the slot 14a out of alignment with arm 11. As stated, spring 17 provides friction on sleeve 14 so that it is not too easily moved.

From the above description it will be seen that I have provided a very simple and efficient structure of steering mechanism for an outboard motor. As above stated, handle 12 functions both as a steering handle and also as a carrying handle for the motor. Handle 12 is quite easily and readily moved and is locked in its carrying position by sleeve 14. When handle 12 is in steering position the end 11a extends into stem 12a and forms an efficient reinforcement for the handle. A very strong and rugged construction is thus provided. There is no danger of handle stem 12a being broken at pivot 13. It may be desirable at times for the operator to swing handle 12 to the position shown in Fig. 6 if said handle should happen to be in the way of the boat occupant. Handle 12 is also so moved up for boxing and transporting. The device has been

amply demonstrated in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. In an outboard motor structure having a steering arm; a handle pivoted adjacent its end to said arm, said handle having a slot extending longitudinally therein at said end, said arm having a portion receivable in said slot, a pivot connecting said arm and handle and extending transversely thereof, said handle being movable to position in substantial longitudinal alignment with said arm and to position substantially at right angles to said arm; and a rotatable sleeve carried on said handle partially surrounding said end portion of said arm and having a slot adapted to receive said end portion when said handle is moved to said first mentioned position, said sleeve being rotatable to bring said slot therein out of alignment with said end portion.

2. A device of the class described comprising a steering arm; a handle having spaced lugs at one end, a pivot extending transversely through said lugs and arm and fitting therein so that said handle has only rotative movement about the axis of said pivot, said handle being movable about said axis to a position in substantial longitudinal alignment with said arm to a position substantially at right angles to said arm, said handle having an opening extending longitudinally therein and said arm having a portion rigid therewith and projecting beyond said pivot toward said handle and receivable in said opening when said handle is in said first mentioned position and disposed out of said opening when said handle is at right angles to said arm; and a member carried on said handle and movable to position to lock said handle in its position at right angles to said arm.

3. A device of the class described having in combination, a steering arm having a flat side, a handle disposed adjacent one end of said arm having laterally spaced lugs at one end; a pivot extending transversely of said lugs and arm and connecting said handle at one end to said arm, said handle being movable to position in substantial longitudinal alignment with said arm and to position substantially at right angles to said arm, said handle having an opening extending longitudinally thereof adjacent said pivot, said arm having a projection receivable in said opening when said handle is in said first mentioned position and movable out of said opening when said handle is in said last mentioned position, and a sleeve carried by said handle and rotatable thereon to have its end ride on said flat side of said arm to prevent said projection entering said opening to lock said handle in said last mentioned position.

4. A device of the class described having in combination, a steering arm, a handle pivoted at one end to said arm and movable to position in substantial longitudinal alignment with said arm and to position at an angle to said arm, said handle having a slot adjacent said pivot, said arm having a projection receivable in said slot, a cylindrical sleeve carried on said handle

and partially embracing said projection, said sleeve having a slot in one side for receiving said projection when said handle is in said first mentioned position, said sleeve being rotatable to bring said slot therein out of alignment with said projection when said handle is in said second mentioned position to lock said handle in said second mentioned position.

5. The structure set forth in claim 4, said pivoted end of said handle being bifurcated and embracing said arm and pivoted thereto by a pivot extending transversely of said handle and arm.

6. A device of the class described comprising a steering arm, a handle having laterally spaced lugs at one end, a pivot extending through said arm and lugs and fitting therein so that said handle is limited to rotative motion about the axis of said pivot said handle being movable about said axis to a position in substantial longitudinal alignment with said arm and to a position substantially at right angles to said arm, said handle having an opening extending longitudinally therein inwardly of said lugs and said arm having a portion extending beyond said pivot toward said handle and disposed in said opening when said handle is in said first mentioned position and disposed out of said opening when said handle is at right angles to said arm, whereby a structure is formed which is very strong and rigid transversely.

7. A device of the class described having in combination, a steering arm, a handle disposed adjacent one end of said arm and having spaced lugs at one end, a pivot extending transversely through said arm and lug and connecting said handle at one end to said arm, said handle being movable to position in substantial longitudinal alignment with said arm and to position substantially at right angles to said arm, said handle having a slot in said end extending longitudinally thereof adjacent said pivot, said arm having a flat projection extending beyond said pivot and adapted to extend into said slot when said handle is in said first mentioned position and to be disposed out of said slot when said handle is at right angles to said arm whereby a strong structure is provided against strains transversely of said handle.

8. A device of the class described having in combination, a steering arm, a handle disposed adjacent one end of said arm, a pivot extending transversely of said arm and handle and connecting said handle at one end to said arm, said handle being movable to position in substantial longitudinal alignment with said arm and to posi-

tion substantially at right angles to said arm, said handle having a slot extending longitudinally therein and transversely thereof adjacent said pivot, said arm having a flat projection extending longitudinally thereof and adapted to extend into said slot when said handle is in said first mentioned position whereby a strong structure is provided against strains transversely of said handle, said arm having a surface inclined to the longitudinal axis thereof and said handle having a surface inclined to the longitudinal axis thereof adapted to engage said first mentioned surface when said handle extends in substantial longitudinal alignment with said arm.

9. A device of the class described having in combination, a steering arm having a flat side, a handle disposed adjacent one end of said arm, a pivot extending transversely of said arm and handle and connecting said handle at one end to said arm, said handle being movable to position in substantial longitudinal alignment with said arm and to position substantially at right angles to said arm, said handle having a slot extending longitudinally therein and transversely thereof adjacent and inwardly of said pivot, said arm having a flat projection extending longitudinally thereof and adapted to extend into said slot when said handle is in said first mentioned position whereby a strong structure is provided against strains transversely of said handle, said handle having a sleeve rotatable thereon adjacent said arm and surrounding said slot, said sleeve having a slot therein adapted to be moved into and out of alignment with said slot in said handle to respectively permit the passage of said flat projection therethrough and having an end adapted to engage said side of said arm to lock said handle in position at right angles to said arm.

MERTON F. SNYDER.
